FIG. 1

FIG. 2

INVENTOR:

W. A. Houston,

Milton S. Grandaell.

ATTORNEY

UNITED STATES PATENT OFFICE.

WILLIAM A. HOUSTON, OF SIOUX CITY, IOWA.

DESIGN FOR A HOOK-PIN.

55,515.

Specification for Design. **Patented June 22, 1920.**

Application filed February 16, 1920. Serial No. 359,189. Term of patent 3½ years.

To all whom it may concern:

Be it known that I, WILLIAM A. HOUSTON, a citizen of the United States, and a resident of Sioux City, in the county of Woodbury and State of Iowa, have invented a new, original, and ornamental Design for Hook-Pins, of which the following is a specification, reference being had to the

accompanying drawing, forming a part thereof, and of which Figure 1 is a front elevation and Fig. 2 is a side elevation.

I claim:

The new and original design for a hook-pin as shown.

WILLIAM A. HOUSTON.
